UNITED STATES PATENT OFFICE

WILLIAM A. HUGHES, OF MORRISTOWN, NEW JERSEY, ASSIGNOR TO COOPER HEWITT ELECTRIC COMPANY, OF HOBOKEN, NEW JERSEY, A CORPORATION OF NEW JERSEY

APPARATUS FOR TREATING PATENT LEATHER

Application filed September 22, 1926. Serial No. 137,109.

The present invention relates to method and apparatus for solarizing varnished hides, that is, for exposing varnished hides to ultra violet light for the drying thereof and the invention particularly relates to a method of and apparatus for maintaining a moist atmosphere for the body of the hide being so treated.

The invention further relates to method and apparatus for keeping hides being solarized from losing moisture during the solarizing process and thereby to keep the hides from shrinking. This is a particular advantage in the case of varnished hides because in this way the area of the hides to which varnish has been applied is kept from decreasing, and buckling and cracking of the varnished hide is prevented.

Various other objects and advantages of the invention will be obvious from the following particular description of one form of apparatus embodying the invention or from an inspection of the accompanying drawings; and the invention also consists in certain new and useful methods and features of construction and combinations of parts hereinafter set forth and claimed.

In the accompanying drawings there is shown for purposes of illustration one form of apparatus embodying the invention, in which

Fig. 1 is a sectional elevation view taken along the line 1—1 of Fig. 2,

Fig. 2 is a longitudinal elevation view in section taken along the line 2—2 of Fig. 1,

Fig. 3 is a longitudinal elevation view of an alternative form of moisture supplying means and

Fig. 4 is a vertical elevation view taken along the line 4—4 of Fig. 3.

In the drawings the casing or tunnel enclosure 1 supports on each of its longitudinal sides a bank of lamps 2, 2 which are sources of light rich in ultra violet light. These lamps are indicated as being of the quartz type mercury vapor lamp. Above each bank is mounted a longitudinal support or track in the form of an angle iron 4 which extends from one end of the tunnel casing 1 to the other. Above said tracks 4, 4 and from one

end to the other of the tunnel there is mounted a pair of endless chains 6, 6 on shafts 8, 8, suitable means not shown being provided for driving said shafts and chains as through the gear 10. Mounted across said chains at intervals are the cross bars 12, 12 each of which carries at each of its ends a roller 13, 13 designed to travel over its respective track 4 and support the bar 12. Between its ends each of said bars 12, 12 carries a pair of longitudinal supporting pins 15, 15 spaced from the bar 12 and mounted thereto by means of lugs 16. Said pins 15, 15 serve for carrying hide stretching frames 18 which are mounted thereonto by means of hooks 20, 20 mounted to one side thereof. By these means stretched and varnished hides can be spaced apart and mounted in two rows extending the length of the treating chamber 1. Longitudinally through the center of chamber 1 and near the top thereof extends the water pipe 22 which throughout its length is provided with small openings 24, 24. Along said pipe 22 is hung a curtain 26 of canvas, felt or other suitable material by means of a loop 28 formed along one edge thereof. Said openings 24 are shown in the drawings as being along the bottom of the pipe but when desired as for preventing spattering and for controlling the flow these holes are spaced at portions of the pipe covered by said loop 28. Said curtain 26 is shown as being in sections for convenience in handling but when necessary or desired it can be in one piece extending the desired length of the treating chamber. This curtain 26 extends vertically through a distance great enough to present moisture to all parts of hides mounted thereat or moved thereby. At the bottom of the chamber and below the lower edge of the curtain is provided the drain trough 30. The distance between the curtain 26 and the hides 32 is made to be from a fraction of an inch up to a foot or more to suit natural and other working conditions.

In the use and operation of this embodiment of the invention the varnished hides for making patent leather for example are mounted with the varnished side toward the lamps 2, 2 and the other side toward the mois-

ture curtain. The hides can be treated with the ultra violet light either while being carried through the chamber 1 by means of the said chains 6, 6 or while being supported stationary thereby, this depending upon the length of chamber 1, time required for treating, and other conditions and factors. During such treating the lamps 2, 2 are energized and illuminated in a manner well known in the art to produce ultra violet radiations, they being spaced at a suitable distance from the hides 32, 32. During the treatment water is circulated through said pipe 22 at a rate suitable for maintaining said curtain 26, 26 moist for the purpose of maintaining hides in suitable and desired moist conditions and for the purpose of preventing evaporation from the hides of natural moisture and of oils and so on, the presence of which are important factors in determining the length of life of the varnished hides and of finished material made thereof. In some cases the curtains 26, 26 are moistened or wetted before or at the beginning of or during the hide treating process and the water then shut off from the pipe 22 until further moisture is necessary in the same or another batch of hides. In other cases the water is caused to flow or trickle over the curtain 26, 26 to maintain and supply the necessary moisture to keep the hides in proper condition.

In Figs. 3 and 4 are illustrated an alternative means for supporting the moisture curtains 26, 26 in which the feed pipe 22' has fixed thereto auxiliary pipes 35, 35 which extend parallel thereto and which are of comparatively short length to suit convenient removal and replacement of said curtains 26, 26. As shown in the drawings said pipes 35, 35 are arranged below the pipe 22' but in certain cases as for positioning the curtains 26, 26 at desired distances from the hides said pipes 35, 35 are positioned laterally along said main pipe 22'.

Although I have shown and described and have pointed out in the annexed claims certain novel features of the invention, it will be understood that various omissions, substitutions and changes in the several steps of the process and in its operation and in the form and details of the apparatus illustrated may be made by those skilled in the art without departing from the spirit of the invention.

I claim:

1. In combination in apparatus for treating varnished hides, an artificial source of light rich in ultra violet rays and means for exposing an extended area of water parallel to the position of hides therein.
2. In combination in apparatus for treating varnished hides, an artificial source of light rich in ultra violet rays and means for exposing an extended area of water along

the position of hides therein and closely adjacent thereto.

3. In combination in apparatus for treating varnished hides an artificial source of light rich in ultra violet rays, means for supporting hides in position to be exposed to said source, and means for supplying water vapor to the exposed hides comprising means for extending water over an appreciable area substantially parallel to hides being treated

70
75

4. In combination in apparatus for treating varnished hides, an artificial source of light rich in ultra violet rays, means for supporting hides in position to be exposed to said source, and means for supplying water vapor to the exposed hides comprising means for extending water over an appreciable area substantially parallel to hides being treated

80

5. In apparatus for treating varnished hides with ultra violet light means for supplying water vapor to the atmosphere at such hide or hides comprising a curtain extending substantially parallel to the hide and means for flowing water over the surface of said curtain.

85
90

6. In apparatus for treating varnished hides with ultra violet light, in combination, a source of artificial light rich in ultra violet rays, means for supporting stretched hides for exposure to said light and means for supplying water vapor to the hides being exposed comprising a blanket extending substantially parallel to the hides at the side thereof opposite to said light source and means for keeping said blanket moistened.

95
100

7. In apparatus for treating varnished hides with ultra violet light, in combination, a source of artificial light rich in ultra violet rays, means for supporting stretched hides for exposure to said light and for conveying the stretched hides in continuous succession past the light source and means for supplying water vapor to the hides being exposed comprising a blanket extending substantially parallel to the hides at the side thereof opposite to said light source and means for keeping said blanket moistened.

105
110
115

8. In apparatus for artificially solarizing varnished hides, in combination, a source of light rich in ultra violet rays, a blanket of such material as canvas, felt and the like extending over an appreciable area, means for wetting said blanket, and means for supporting hides between said source and said blanket with the side to be solarized toward said light source.

120
125

9. In apparatus for artificially solarizing varnished hides, in combination, a source of light rich in ultra violet rays, a blanket of such material as canvas, felt and the like extending over an appreciable area, means for wetting said blanket and means for conveying hides in successive progression between

120

said source and said blanket with the side to be solarized toward said light source.

10. The process of treating varnished hides comprising maintaining a water supply in proximity to said hides and applying water from said supply over an appreciable area substantially parallel to said hides but out of contact therewith.

11. The process of treating varnished hides comprising maintaining a water supply in proximity to said hides and applying water from said supply over an appreciable area substantially parallel to said hides, and subjecting said hides to artificially generated ultra violet rays.

15. 12. In apparatus for treating varnished hides, means for supplying water vapor to the atmosphere at the hides comprising a curtain extending substantially parallel to the 20 hides and means for supplying water to the surface of said curtain.

Signed at Hoboken in the county of Hudson and State of New Jersey this 21st day of September A. D. 1926.

25 WILLIAM A. HUGHES.
